United States Patent Office

Des. 196,777
Patented Nov. 5, 1963

196,777

STOCK WATERING TANK

Harry E. Haynes, Evergreen, Colo., assignor to The Empire Corporation, Adams City, Colo., a corporation of Colorado

Filed May 14, 1962, Ser. No. 70,120

Term of patent 14 years

(Cl. D12—2)

Fig. 1

Fig. 2

Fig. 3

FIG. 1 is a perspective view of a stock watering tank, showing my new design;

FIG. 2 is a top plan view thereof drawn to a slightly reduced scale; and

FIG. 3 is a front elevation thereof drawn to the same scale as FIG. 2.

I claim:

The ornamental design for a stock watering tank, as shown.
